FOLDING FENCE

Arthur E. May, Jr., Lake Grove, and Boris Michael Fingerut, Coos Bay, Oreg.

Application August 9, 1954, Serial No. 448,483

6 Claims. (Cl. 256—33)

Our present invention comprises a foldable fence, of 15 particular utility as a protector or support for garden plants, consisting of a plurality of identical wire frames and which is easy and economical to form and assemble in mass production.

An important object of the present invention is to 20 provide a fence of the foregoing character which may be compactly packaged.

Another object of the present invention is to provide a folding wire fence which may be folded in accordion fashion in either direction, so that no difficulty is experienced in folding the fence into a compact package, either for initial shipment, or for storage between periods of use by the owner.

A further object of the present invention is to provide a fence of the foregoing character comprising a plurality of frames held together by snap hook means formed on each frame, in which each frame comprises a pair of snap hooks turned in the same direction whereby the hooks may be formed in a single operation of a single forming die, and which hooks are so arranged as to permit the folding of the fence in either direction with equal ease and equal resulting compactness.

A still further object of the present invention is to provide a fence of the foregoing character which is formed of a plurality of identical sections or frames, whereby the fabrication of fences of any length involves the manufacture of a single type of frame.

A further object of the present invention is to provide a fence of the foregoing character which may be readily tailored to fit the immediate purposes of a user such as a gardener, without the necessity of supplying special links or other devices for joining several lengths of fence together, and whereby a single length of fence may be readily broken up into shorter lengths as desired.

The foregoing and other objects and advantages of the present invention will be more readily apparent from inspection of the accompanying drawings taken in connection with the following specification wherein like numerals refer to like parts throughout, and in which a preferred form of the present invention is illustrated.

In the drawings,

Fig. 1 is a perspective view of a section of fence fabricated in accordance with the present invention as used to protect a plant;

Fig. 2 is an enlarged view in elevation of a portion of the fence, with the end frame folded back over the next adjacent frame;

Fig. 3 is an enlarged end elevation of a single frame of the fence;

Fig. 4 is a horizontal section taken substantially along line 4—4 of Fig. 2;

Fig. 5 is an enlarged horizontal section taken substantially along line 5—5 of Fig. 2; and

Fig. 6 is a plan view of four sections of fence folded upon themselves into a compact bundle.

The fence illustrated in Fig. 1 comprises a plurality of identical wire frames 10, each of which consists of an

2

upright wire 11 affixed to a wire form comprising an intermediate upright portion 12, an upper arm 13, and a lower arm 14. The arms 13 and 14 are identical, extend in the same direction from the upper and lower ends respectively of the upright portion 12, and terminate respectively in snap hooks 15 which are formed by bending the tips of the arms back to provide open bights. As seen most clearly in Fig. 5, the hooks 15 are elongated whereby considerable lateral play between fence frames is provided, and the mouths of the hooks are constricted sufficiently to prevent accidental separation of the frames. However, the wire from which the forms are fabricated is sufficiently resilient to permit forceful snapping together, or unsnapping, of the frames at any joint of the fence. The arms 13 and 14 are slightly inclined toward each other whereby the form defines three sides of a regular trapezoid, and whereby the hooks 15 may be readily engaged respectively with the upper and lower portions of the upright portion 12 of an adjacent frame.

The upright wire 11 is affixed to the arms 13 and 14 so as to be parallel to the upright portion 12 of the form, the affixing being preferably accomplished by welding, the welds being indicated at 20 and 21, respectively. The upright wires 11 project sufficiently below the lower arms 14 to provide unobstructed legs 16 which may be forced into the ground to hold the fence in position, and the tips of the legs may be pointed to facilitate their entry into hard ground, the pointed tips being indicated at 22. The upper end of each of the upright wires 11 is bent back to provide an open bight 17 lying generally in the plane of the frame and providing an ornamental effect at the top of the fence, and also providing a rounded handle at the top of each frame to facilitate handling of the fence, and forcing of the legs 16 into the ground. The free tip 18 of the bight 17 lies close to the surface of the upper arm 13, but is not affixed thereto, whereby the tip 18 may be sprung in either direction from its normal position directly above the arm 13.

The upright wire 11 is preferably affixed to the arms 13 and 14 so as to be offset slightly from the vertical centerline of the wire form, as illustrated being offset toward the upright portion 12, whereby when two frames are folded upon themselves as shown in Figs. 2, 4 and 6, the upright portions 11 will naturally fall side by side, thereby permitting the packaging of the fence in a small, compact bundle. Due to their sloping arrangement, the upper and lower arms cross each other when the fence is folded. The adjacent portions of the upper arms engage the tips 18 and slightly spring the tips aside in either direction, depending upon the direction of folding of the fence. The uprights may be situated along the vertical centerline of the section, in which case folding in the manner illustrated may nevertheless be accomplished due to the elongated bights of the hooks 15 permitting the uprights to be placed side by side rather than requiring them to fall upon each other.

The desired plurality of frames are assembled by snapping them together as described, and the fence is folded into a compact package and restrained by a tie or wrapper label. The purchaser may use the entire fence, or may break it into any number of sections according to his needs. The purchaser may also snap together several fences in order to form a long fence. There are no special joining members required, and the fence may be broken up at any point without requiring the user to hunt for a special joint.

Having illustrated and described a preferred embodiment of the present invention, it should be apparent to those skilled in the art that the same permits of modification in arrangement and detail. We claim as our invention all such modifications as come within the true spirit and scope of the appended claims.

We claim:

1. A foldable fence comprising a plurality of identical wire frames, each of said frames comprising an upright wire adapted to be thrust into the ground, and a wire form affixed to said upright wire, said wire form comprising an intermediate upright portion and a pair of arms extending laterally from the top and bottom respectively of said upright portion, said arms lying in an upright plane passing through said upright portion, extending in the same direction from the upright portion, and being inclined toward each other, whereby said form defines three sides of a regular trapezoid, each of said arms having an open snap hook at its end releasably embracing the upright portion of the wire form of an adjoining frame.

2. A foldable fence comprising a plurality of identical wire frames, each of said frames comprising an upright wire adapted to be thrust into the ground, and a wire form affixed to said upright wire, said wire form comprising an intermediate upright portion and a pair of integral arms extending laterally from the top and bottom respectively of said upright portion, said arms lying in an upright plane passing through said upright portion, extending in the same direction from the upright portion, and being inclined toward each other, whereby said form defines three sides of a regular trapezoid, the end of each of said arms having an open snap hook embracing the upright portion of the wire form of an adjoining frame, said hooks being elongated to permit play between interconnected frames.

3. A foldable fence comprising a plurality of identical wire frames, each of said frames comprising an upright wire adapted to be thrust into the ground, and a wire form affixed to said upright wire, said wire form comprising an intermediate upright portion and a pair of integral arms extending laterally from the top and bottom respectively of said upright portion, said arms lying in an upright plane passing through said upright portion, extending in the same direction from the upright portion, and being inclined toward each other, whereby said form defines three sides of a regular trapezoid, the end of each of said arms being bent back in the same direction in planes at right angles to said upright plane to provide open snap hooks embracing the upright portion of the wire form of an adjoining frame, said upright wire being parallel to said upright portion of the wire frame and located on the side of the plane of said wire frame toward which said hooks extend.

4. A foldable fence comprising a plurality of identical wire frames, each of said frames comprising an upright wire adapted to be thrust into the ground, and a wire form affixed to said upright wire, said wire form comprising an intermediate upright portion and a pair of integral arms extending laterally from the top and bottom respectively of said upright portion, said arms lying in an upright plane passing through said upright portion, extending in the same direction from the upright portion, and being inclined toward each other, whereby said form defines three sides of a regular trapezoid, the end of each of said arms being bent back in the same direction in planes at right angles to said upright plane to provide open snap hooks embracing the upright portion of the wire form of an adjoining frame, said upright wire being

parallel to said upright portion of the wire frame and located on the side of the plane of said wire frame toward which said hooks extend, and said upright wire being slightly offset from the vertical centerline of said wire frame.

5. A foldable fence comprising a plurality of identical wire frames, each of said frames comprising an upright wire adapted to be thrust into the ground, and a wire form affixed to said upright wire, said wire form comprising an intermediate upright portion and a pair of integral arms extending laterally from the top and bottom respectively of said upright portion, said arms lying in an upright plane passing through said upright portion, extending in the same direction from the upright portion, and being inclined toward each other, whereby said form defines three sides of a regular trapezoid, the end of each of said arms being bent back in the same direction in planes at right angles to said upright plane to provide open snap hooks embracing the upright portion of the

10 wire form of an adjoining frame, said upright wire being parallel to said upright portion of the wire frame and located on the side of the plane of said wire frame toward which said hooks extend, and said upright wire having its upper end bent into an open bight lying generally in the 15 plane of the frame and having its tip terminating close to the upper surface of the upper one of said arms.

20 6. A foldable fence comprising a plurality of identical wire frames, each of said frames comprising an upright wire adapted to be thrust into the ground, and a wire form affixed to said upright wire, said wire form comprising an intermediate upright portion and a pair of integral arms extending laterally from the top and bottom respectively of said upright portion, said arms lying in an upright plane passing through said upright portion, 25 extending in the same direction from the upright portion, and being inclined toward each other, whereby said form defines three sides of a regular trapezoid, the end of each of said arms being bent back in the same direction in planes at right angles to said upright plane to provide open snap hooks embracing the upright portion of the wire form of an adjoining frame, said hooks being elongated to permit play between interconnected frames and constricted at their mouths to an extent to prevent accidental separation of interconnected frames, the wire of said 30 forms being sufficiently resilient to permit forceful association and disassociation of the frames, said upright wire being parallel to said upright portion of the wire frame, located on the side of the plane of said wire frame toward which said hooks extend, and being slightly offset from the vertical centerline of said wire frame toward said upright portion, and said upright wire having its upper end bent into an open bight lying generally in the plane of the frame and terminating slightly above the hooked 35 end of the upper one of said arms.
